UNITED STATES PATENT OFFICE.

BERTELL W. KING, OF BROOKLYN, NEW YORK.

MEANS FOR INSCRIBING UNEXPOSED PHOTOGRAPHIC FILMS, PLATES, OR THE LIKE.

1,351,762.

Specification of Letters Patent.

Patented Sept. 7, 1920.

Application filed March 11, 1915. Serial No. 13,582.

To all whom it may concern:

Be it known that I, BERTELL W. KING, a citizen of the United States, residing in Brooklyn, county of Kings, State of New York, have made a certain new and useful Invention in Means for Inscribing Unexposed Photographic Films, Plates, or the like, of which the following is a specification.

This invention relates to means for supplying inscriptions to unexposed photographic films, plates or the like.

The object of the invention is to provide a device which will permit writing or printing on or otherwise marking or inscribing an unexposed film or plate as used in photography, which is simple in construction, efficient in operation and cheap to manufacture.

Other objects of the invention will appear more fully hereinafter.

The invention consists substantially in the construction, combination, location, and relative arrangement of parts all as will be more fully hereinafter set forth, as shown on the accompanying drawing, and finally pointed out in the appended claims.

Referring to the drawing,—

Figure 1 is a plan view showing the back or bottom of a film camera embodying my invention.

Fig. 2 is a sectional view taken on the line 2—2, Fig. 1, and looking in the direction of the arrows.

Fig. 3 is an enlarged detail broken view of a portion of the construction embodying my invention.

Fig. 4 is a view taken on the line 4—4, Fig. 3, and looking in the direction of the arrows.

Fig. 5 is a diagrammatic view showing a circuit arrangement employed in connection with my invention.

Fig. 6 is a plan view of the electric light bulb and attachment as employed in connection with my invention.

The same part is designated by the same reference numeral wherever it occurs throughout the several views.

In photography it is often desirable to print, mark, or otherwise inscribe on the plate or film employed before or after a picture is taken, the name of the place photographed, the date, the autograph of the person photographed, or other distinguishing or designating inscriptions. In the use of plate cameras, the method heretofore

employed consists of marking in chalk or pencil upon the plate holder, the desired inscription. It is evident that such inscriptions so made, do not appear upon the photo- 60 plate when developed, nor upon the photo- print made from the developed plate. In order that such inscription shall appear upon the plate when developed, or the print made therefrom, it is necessary to scratch 65 the desired inscription upon the plate or else write or print the same on each individual print. These methods are all objectionable. Where the holder itself is marked there is the danger of the marks becoming obliterated, or remaining thereon when another 70 picture is taken, thereby causing confusion. Where the desired inscription is scratched upon the plate this can be done only after the plate is developed and not at the time 75 the exposure is made. This incurs the danger of the operator forgetting the desired inscription during the time or period intervening the exposure and development. Where each individual print is separately 80 inscribed, it involves tedious labor and increased expense and separate handling of each individual print. Further, when photographic films are employed in long reels or rolls, as in motion photography, it is necessary 85 to mark on a roll of film that has been exposed and used in taking pictures of a particular scene or locality, the number of the scene, or the name of the place photographed, or any other notation employed by 90 the various motion picture producing operators, to distinguish one reel from the other. It has been the practice heretofore, at the completion of a "run" of a scene, for the operator to open the camera, and make the 95 desired notation on a film, and to then close the camera in preparation for the next run of film. In this practice, not only the particular film upon which the notation is made is wasted, but also from two to three feet of 100 film is exposed and destroyed by the resulting exposure thereof to light when the camera box is opened, and are, in consequence, also wasted. It will be readily seen that in motion photography where, during 105 the day, several hundreds of runs are made by each operator, the waste of from two to three feet of film at each run amounts to a large item of needless waste and expense.

In the use of film cameras, such as the 110 well known kodaks and the like, in which are used film packs or rolls which usually

allow from six to twelve or more individual exposures or pictures, it is often desirable to write or print on each individual film portion which forms a part of the individual exposure, the desired inscription. It is also desirable to write or print the desired inscription upon the unexposed film so that such writing will be reproduced upon each print made from the negative. Various ways have been suggested for accomplishing this, such as providing the camera casing with a slot opening upon a portion of the film reel, so that sharp pointed steel pencil or punch may scratch through the light excluding wrapper over the film, which wrapper is exposed through the slot referred to, and thus, by allowing the daylight to pass through the portion of the wrapper so scratched, expose the film in accordance with the scratching.

The disadvantages of this method are obvious. The steel pencil point may become dull, and not make a clean cut through the wrapper, or the pencil point might be pressed with too great a force through the wrapper and cut through the film itself thereby injuring and weakening it. Further a loose, individual member, namely the pencil, must be provided, and being independent of the camera, is apt to be lost, or misplaced. The greatest disadvantage encountered, however, is that, due to the cutting action necessary, it is practically impossible to write in one's individual and characteristic handwriting, upon the film, without tearing the wrapper, and exposing and spoiling the film.

It is among the special purposes of my invention to provide a unitary arrangement 40 permanently attached to a camera wherein it is possible to transmit any writing of any desired characteristic to the film or plate negative before it is exposed, without exposing any portion of the plate or film or light excluding wrapper to the daylight, and without injuring the film or the wrapping by cutting or piercing action.

In carrying out the objects of my invention I propose to employ the usual camera, which in this instance is shown for illustrative purposes to be a well known collapsible camera or kodak film camera comprising a frame or casing 7 in which is mounted at its ends the usual film rollers 8, 10, and provided with the usual hole or opening 9 for determining how far the film must be turned by the roller which is winding up, after an exposure has been made, to place a new and unexposed film surface behind the camera lens, in the usual and well known manner. In the form shown, the roller 8 has wound around it the new or unexposed film, and the film 11 passes therefrom and extends through a suitable slot or 65 passage 12 as shown in Fig. 2, to the roller

10, as indicated in dotted lines, Fig. 1. Suitably mounted in the camera casing 7 is a tubular shaft 13 extending into the wooden casing 7, and projecting slightly above the exterior surface of the casing. Passing 70 through the tubular shaft 13 is a pin or shaft 14 provided at its ends with screw threads. It will be seen that the shaft 14 may be rotated independently of the rotating action of the shaft 13. Suitably attached to, or forming a part of the shaft 13 are arms or rigid limbs 15, 16. Suitably keyed to the shaft 14, and held thereon by means of nuts 17 are links or arms 18 and 19. The links or arms 18, 15, and 16, 19, 80 are secured together by rivets or the like 20 which also serve to secure thereto, similar links or arms, forming a well known form of lazy tongs or pantograph, the upper lazy tongs member 15, 18, acting outside of the 85 casing 7, and the lower lazy tongs member acting inside of the camera through a slot 22 formed for that purpose in the interior of the wooden camera frame or casing 7. It will be readily seen, that due to the arrangement of the shafts 13, 14, and their respective lazy tongs attachments, any movement in any direction at the extremity 23 of the outside lazy tongs will be transmitted and identically reproduced at the extremity 95 of the lower or inside lazy tongs arrangement 16, 19.

The extremity 30 of the upper lazy tongs consists of a point of steel or other conducting material such as lead or the like, and 100 is provided with a knob or handle 25 to facilitate the writing movements of the lazy tongs.

The extremity 24 of the lower lazy tongs carries a small electric light bulb 26. This 105 bulb is coated over with a layer of any suitable light excluding material such as black paint except for a small pin point portion 27 which is so positioned as to be the nearest point of the bulb to the film 11. The tubular shaft 13 and the shaft 14 are of such length that the bulb 26 is held in close proximity to the film 11 throughout its extension across the width of the film to its extended position.

Suitably mounted in the bottom or back portion of the camera casing, and opposite to the shafts 13, 14, is a plate 28 of suitable conducting material of a length approximately the same as the width of the film 11, 120 and of any desired width. For the purposes of illustration, I have shown this plate as being sufficiently wide to allow several lines of written matter, but my invention is not to be limited in this respect.

The plate 28 is connected to one terminal of a source of current such as a battery 29. The other terminal of the current source is connected to the filament of the electric light bulb which in turn is electrically con- 130

nected in series to the lazy tongs members 16, 19 in any suitable manner. The current flows through the members 16, 19, the shafts 13, 14, lazy tongs 15, 18, to the conducting point 30. The shafts 13, 14, project sufficiently above the surface of the camera casing to hold the lazy tongs elements 15, 18, when in extended position a sufficient distance from the surface of the camera casing to hold the stylographic device or pencil 30 normally out of contact with the conductor plate 28, but the resiliency of the elements 15, 18, allows the pencil or point to be depressed to make contact with the plate 28 and thereby complete the electric circuit and cause the lamp 26 to light.

The battery may be carried in any suitable place either exteriorly or internally with respect to the camera casing. I have shown one arrangement wherein the battery 29 is inserted in a pocket in the casing 7. In this instance, I provide a door 32, hinged at 33, to allow ready access to the battery, for the purpose of replacing the battery whenever it becomes depleted.

It is evident that when the writing device is not to be used, it is folded up as partially indicated in dotted lines, Fig. 1, into a small amount of space, it being understood, that when the outside lazy tongs elements are thus folded up toward their fixed point, the inside elements are likewise folded up and, together with the electric light bulb, are out of the scope of the light rays which cause the print on the film.

The operation of the device is comparatively simple. Assuming that a film has been exposed, and the picture taken, and it is desired to inscribe on the picture taken, the lazy tongs arrangement is in its folded or condensed position. The operator takes the knob or handle 25 and extends the lazy tongs arrangement to its extended position, as shown in Figs. 1 and 2. The inscription is then made as in the use of an ordinary pantograph pencil, pressing down upon the handle 25 sufficiently to form contact between the point 30 and the plate 28. As long as this contact is maintained, the electric light bulb remains lighted and as the bulb passes close to the film, the light rays pass from the pin point opening 27 through the light excluding film cover or coating over the bulb. The light rays passing over the film in identical reproduction of the movement of the point 30, expose that portion of the film that the light rays pass over, and consequently, when the film is developed, the autographed inscription is reproduced on the developed negative. Each print produced from the film or plate will of course bear a reproduction of the autographed inscription.

While I have shown and described in detail one construction and arrangement em-

bodying my invention, it will be understood many changes in details might occur to one skilled in the art without departing from the broad scope of my invention as defined in the claims and while I have shown and described my invention as applied to a film camera or a kodak it will be understood that my invention is not to be limited thereto, as the same is applicable to plate cameras, motion picture cameras, and, in fact, to any type of camera used in modern photography.

Having now set forth the objects and nature of my invention, and having shown and described an arrangement embodying the same what I claim as new and useful and of my own invention and desire to secure by Letters Patent, is,—

1. A camera adapted to contain a sensitized element in combination with means including lazy tongs and a source of artificial light for identically reproducing script or other writings upon said sensitized element.

2. A camera adapted to contain a sensitized element in combination with means including a source of artificial light for reproducing script or other writings upon that surface of said sensitized element which is exposed through the lens of said camera.

3. A camera adapted to contain a sensitized element in combination with a pair of lazy tongs, means for transmitting the motion of the end of one lazy tongs to the end of the other lazy tongs, to reproduce upon said sensitized element the path of movement of the end of said first mentioned lazy tongs.

4. A camera including a casing and adapted to contain a sensitized element inclosed therein in combination with a lazy tongs located outside of said casing and a lazy tongs located inside of said casing, means for connecting said lazy tongs together whereby the path of travel of the free end of said outside lazy tongs is geometrically followed by the free end of said inside lazy tongs, and means located at the free end of said inside lazy tongs for exposing said sensitized element to a ray of light along the line of the corresponding line of the path of travel of the free end of said outside lazy tongs.

5. A camera including a casing and adapted to contain a sensitized element inclosed therein in combination with a lazy tongs located outside of said casing and a lazy tongs located inside of said casing, means for connecting said lazy tongs together whereby the path of travel of the free end of said outside lazy tongs is geometrically followed by the free end of said inside lazy tongs and an electric light located at the free end of said inside lazy tongs for exposing said sensitized element to a single ray of light therefrom along the line

of the corresponding line of the path of travel of the free end of said outside lazy tongs.

6. A camera including a casing and adapted to contain a sensitized element inclosed therein in combination with a lazy tongs located outside of said casing and a lazy tongs located inside of said casing, means for connecting said lazy tongs together whereby the path of travel of the free end of said outside lazy tongs is geometrically followed by the free end of said inside lazy tongs, electrically operated means located at the free end of said inside lazy tongs for exposing said sensitized element to a single ray of light along the line of the corresponding line of the path of travel of the free end of said outside lazy tongs.

7. A camera including a casing and adapted to contain a sensitized element inclosed therein in combination with a lazy tongs located outside of said casing and a lazy tongs located inside of said casing, means for connecting said lazy tongs together whereby the path of travel of the free end of said outside lazy tongs is geometrically followed by the free end of said inside lazy tongs, electrically operated means located at the free end of said inside lazy tongs for exposing said sensitized element to a single ray of light along the line of the corresponding line of the path of travel of the free end of said lazy tongs and means for controlling said electrically operated means.

8. A camera including a casing and adapted to contain a sensitized element inclosed therein in combination with a lazy tongs located outside of said casing and a lazy tongs located inside of said casing, means for connecting said lazy tongs together whereby the path of travel of the free end of said outside lazy tongs is geometrically followed by the free end of said inside lazy tongs, electrically operated means located at the free end of said inside lazy tongs for exposing said sensitized element to a single ray of light along the line of the corresponding line of the path of travel of the free end of said outside lazy tongs, the free end of said outside lazy tongs controlling said electrically operated means.

9. A camera including a casing and adapted to contain a sensitized element inclosed therein in combination with a conductor plate attached to said casing, and connected to a source of electric current, a pair of lazy tongs attached to said casing and to each other to allow an electric current to flow therebetween, one of said lazy tongs being located outside of said casing and the other being located inside of said casing, an electric light bulb secured to the free end of said inside lazy tongs and in

electrical conducting relation therewith, said electric light bulb being also connected to said source of electric current, the free end of said outside lazy tongs being held normally out of contact with said plate, so that when and as long as the free end of said outside lazy tongs is in contact with said plate, said electric light bulb is lighted.

10. In an electrically operated device of the character referred to, a normally open electric circuit having terminals consisting of a conducting plate and a conducting pencil, and including in series relation to each other, a source of electric current, an electric light bulb, a pair of lazy tongs, and means adapted to support a sensitized element interposed between said lazy tongs.

11. A camera casing adapted to inclose a sensitized element, in combination with means including a source of artificial light located within the casing to inscribe upon the sensitized element and means located outside the casing for controlling the inscribing means.

12. A camera casing adapted to inclose a sensitized element, in combination with means for exposing the sensitized element to an artificial light point within the casing, and means for controlling the movements of the artificial light point.

13. A camera casing adapted to inclose a sensitized element, in combination with means for exposing the sensitized element to an artificial light point within the casing, and means for controlling from outside the casing the movements of the artificial light point.

14. A camera casing adapted to inclose a sensitized element, in combination with means for exposing the sensitized element to an artificial light point within the casing, a freely movable stylographic device located outside the casing, and connections between said device and the artificial light point to duplicate in the latter the movements of the former.

15. A camera casing adapted to inclose a sensitized element, in combination with means including a source of artificial light for applying an inscription to the sensitized element within the casing, a stylographic device outside the casing, and connections intermediate said stylographic device and inscription means to duplicate in the latter the movements of the former.

16. The combination, with a camera adapted to have a piece of sensitized material disposed therein, of means comprising an electric light pencil for writing directly upon said sensitized material, a source of current for said light, means on the outside of the camera for guiding said light pencil, an electric circuit connection between said guiding means, source of current and light pencil, and means controlled by the guiding

means for completing the circuit through said light.

17. The combination, with a camera adapted to have a piece of sensitized material disposed therein, of means comprising an electric light pencil for writing directly upon said sensitized material, a source of current for said light, a conductor and guiding pencil upon the outside of the camera, means for electrically connecting said light pencil, guiding pencil and source of current, and means controlled by the guiding means for controlling the operation of said light pencil.

18. An autographic recorder for cameras adapted to have a sensitized film therein, comprising a movable element exterior of the camera, and means including a source of artificial light, interior of the camera, for reproducing the movements of said element upon the surface of said film.

19. An autographic recorder for cameras adapted to have a sensitized film therein, comprising a movable lever on the exterior of said camera, and means including a source of artificial light within said camera actuated by said lever to register the movements thereof on said film.

20. An autographic recorder for cameras adapted to have a sensitized film therein, comprising a movable element upon the exterior of said camera, and means including an electric lamp actuated thereby, within said camera, for directing a ray of light from said lamp over said film to correspond to the movements of said movable element.

21. The combination, with a light box adapted to have a piece of a sensitized material disposed therein, of a source of artificial light within the box for supplying a light beam directly to said material, a pencil, means for operatively connecting said source of light and pencil without the box together

whereby said source of light will execute the movements made by the pencil without the 45 box.

22. In a camera, the combination of an electric lamp located within the camera box, a movable support for the lamp, and means exterior to the box to impart movement to 50 said lamp to cause the tracing of light therefrom over the sensitized surface in the camera.

23. In a camera, the combination of an electric lamp located within the camera box, 55 a movable support for the lamp, means exterior to the box to impart movement to said lamp to cause the tracing of light therefrom over the sensitized surface in the camera, and means associated with said exterior lamp moving means to open and close the lamp circuit.

24. In a camera, the combination of an electric lamp located within the camera box, a movable support for the lamp including 65 a lever, a similar lever accessible from the exterior of the camera, connections between said levers, whereby movement of one is duplicated by the other, and a circuit opener and closer for the lamp associated with said 70 exterior lever.

25. An autographic apparatus for cameras, comprising an electric lamp for delivering a circumscribed area of light to the sensitized surface within the camera, an operating device located outside the camera, and a pantographic system of levers connecting said lamp and device. 75

In testimony whereof I have hereunto set my hand in the presence of the subscribing 80 witnesses, on this 9th day of March A. D., 1915.

BERTELL W. KING.
